UNITED STATES PATENT OFFICE.

FRANK WILLIAM CARLSON, OF OILFIELDS, CALIFORNIA.

PUMP-ROD AND CASING HANDLING DEVICE.

Application filed June 8, 1925. Serial No. 35,815.

To all whom it may concern:

Be it known that I, FRANK W. CARLSON, citizen of the United States, residing at Oilfields, in the county of Fresno and State 5 of California, have invented certain new and useful Improvements in Pump-Rod and Casing Handling Devices, of which the following is a specification.

This invention relates to a pump rod and 10 pipe handling device of the character of that shown in my co-pending application, 753,532, filed December 19th, 1924. It was formerly the practice, prior to my previous invention, in removing pump rods from 15 deep wells, to hoist the rods out in "stands", each stand consisting of two or three lengths of pump rod and to lay the stands out upon the ground. A more modern method and 20 the one now commonly employed is to hang these rods from rod hangers which are in turn supported by the usual derrick of the well.

In my pending application, above referred to, a structure is disclosed, by means 25 of which one man can hold the stand of rods during the disengagement of the elevator therefrom and during the time that the stand is being unscrewed from the rods therebelow and transfer such rods to the 30 hangers by which they are supported from the derrick.

The structure of the present invention is 35 designed to accomplish the same result but represents an improvement over my previous construction in that it is adapted to engage the pump rods at any suitable point in their length. In other words, it is not essential that the pump rods have collars formed upon them to be engaged by the device. 40 Since the structure of the present invention is designed to engage a round element such as a rod, it is manifest that it may be used with equal facility upon pipes.

Further objects and advantages of the 45 invention will be set forth in the detailed description which follows.

In the accompanying drawing:

Fig. 1 is a plan view of a rod gripping element constructed in accordance with the 50 invention,

Fig. 2 is a sectional view upon line 6—6 of Fig. 1,

Fig. 3 is a side elevation of the construction,

Fig. 4 is a plan view of one of the gripping rollers hereinafter described,

Fig. 5 is a side view of said roller, and

Fig. 6 is a rear elevation of the jaws by which the gripping rollers are carried.

Like numerals designate corresponding parts in all of the figures of the drawing.

Referring to the drawings, 5 designates a pump rod of conventional form and 6 the rod elevator. The parts so far described are of known construction and the invention 65 resides more particularly in the handling device by which the stand of pump rods (the uppermost one of which is designated at 5 and the others of which are not shown) is transferred from elevator 6 to any suitable suspending device, not shown, but which may correspond to the elevator 6 in construction. The handling device comprises a pair of crossed arms 8 and 9, the outer ends of which constitute handles 10 70 and 11, said arms being pivoted after the manner of tongs upon a bolt 12. The upper end of this bolt is formed with an eye 13 which receives one end of a cable 14. The other end of this cable is attached to the 80 eye 15 of a bolt 16 said bolt being carried by guide bar 17. This bar is secured by a bolt 18 to the arm 8. The bight portion of the cable 14 passes over a pulley 19 the housing 20 of which is suspended from any suitable point upon the derrick, not shown, by means of a suspension cable 21. A spring 85 pressed handle 22 is adapted, when depressed, to draw upon a rod 23 and thereby rock a pawl 24 upon its pivot 25. This pawl engages the teeth 26 of an arcuate rack bar 27, and this pawl and ratchet construction locks the handles of arms 8 and 9 in their closed position, at which time their outer ends 8^a, 9^a are moved towards each 90 other. Jaws 28 and 29 are trunnioned by means of the studs 30 and 31 upon the portions 8^a and 9^a of the arms. These jaws are of U-shape in cross section and constitute 95 housings for tapered, grooved rollers 32, 33 and 34, the first two rollers being carried by the housing 28 and the roller 34 being carried by the housing 29.

The trunnioning of the housings with respect to the portions 8^a, 9^a of the arms, permits a limited rocking movement of these housings with respect to the said arms, though during the process of adjustment of

the apparatus about the rod 5, the jaws are held in approximate horizontal alignment with the arms 8^a, 9^a by means of a spring 35, one end of which is attached to the housing 28 and the other end of which is attached to the arm 8^a. The two housings or jaws are held in proper alignment with each other though being capable of a limited separation, by means of a stud 36, said stud being threaded at 37 into a lug 38, of the housing 28 and entering a slot 39 of the housing 29. (See Fig. 6.) By referring to Fig. 2 it will be seen that the tapering grooved rollers are supported upon studs or shafts 40, 41, which lie at an angle with respect to the vertical and consequently at an angle with the pump rod. Downward movement of the rollers is resisted by springs 43 which are seated in collars 44 and 45. Thus, any downward movement of the pump rod 5, under the influence of gravity, will tend to cause the rollers 33, 34, and in like manner the roller 32, to move downwardly and toward the pump rod and this will, of course, cause a very tight gripping action of these grooved rollers upon the pump rod.

While I have referred to the use of the device upon a pump rod, throughout this specification, it is manifest that the structure can be used to equal advantage upon hollow bodies such as pipes and consequently it is to be understood that the structure is both a pump rod and pipe or casing handling device.

It is particularly to be noticed that the gripping devices are formed as rollers and that these rollers are peripherally grooved. Thus, they exercise their gripping function to prevent vertical movement of the gripped object 5, with respect to them, while at the same time they permit rotation of such gripped object. This is of particular utility in that it enables the user to hold a stand of rods without interfering with the operation of unscrewing the stand of rods from the rods that are still in the well. Thus, if there is any tendency to slip while the rods are being unscrewed, these rollers will act of their own accord, due to their angular disposition to promptly grip the supported object.

An important advantage of this construction is that if the rod stretches under use, which they frequently do, it makes no difference from the operating standpoint since there is flexibility in this construction as to permit the user to raise or lower the stand at will. It is to be understood that the invention is not limited to the precise construction set forth but that it includes within its purview whatever changes fairly come within either the terms or the spirit of the appended claims.

Having described my invention, what I claim is:

1. A device of the character described comprising a pair of members and means for moving them toward and from each other and a plurality of rollers mounted for rotation with respect to said members and mounted upon axes which are inclined with respect to each other.

2. A structure as recited in claim 1 in combination with spring means, tending to move said rollers along said axes in a direction to separate them.

3. A device of the character described comprising a pair of crossed and pivoted arms, a pair of jaws trunnioned in said arms, a plurality of rollers carried by said jaws and mounted upon axes inclined with respect to each other.

4. A device of the character described comprising a pair of crossed and pivoted arms, a pair of housings trunnioned in said arms, a plurality of grooved and tapered rollers mounted upon axes inclined with respect to each other in said housings and means for locking said arms in closed position.

5. A structure as recited in claim 4 in combination with means for holding said housings in substantial horizontal alignment with each other while permitting lateral separation of said housings with respect to each other.

6. A structure as recited in claim 4 in combination with means tending to maintain said housings in horizontal alignment with the arms.

7. A structure as recited in claim 4 in combination with means for suspending said arms in a substantially horizontal plane.

8. A device of the character described comprising a pair of crossed and pivoted arms, a rack bar carried by one of said arms, a pawl carried by the other of said arms, a guide bar carried by one of said arms and guiding the other of said arms, a pair of housings of substantial U-shape in cross section, trunnioned in the inner ends of said arms, a spring tending to maintain said housings in substantial horizontal alignment with the arms, means holding the housings in alignment with each other while permitting limited lateral separation of the housings with respect to each other and a plurality of grooved and tapered rollers mounted upon and carried by said housings said rollers being disposed at an inclination with respect to each other their point of greatest separation being at the top, and a spring bearing beneath said rollers and tending to elevate them.

In testimony whereof I affix my signature.
FRANK WILLIAM CARLSON.
